GRAPPLE

Horace K. Bushnell, Jr., Glen Mills, Pa.

Application August 23, 1949, Serial No. 111,960

9 Claims. (Cl. 294—108)

(Granted under the act of March 3, 1883, as
amended April 30, 1928; 370 O. G. 757)

1

This invention relates to article handling devices and more particularly to carriers for handling and transporting elongated cylindrical objects such as tubes, tanks, projectiles, and the like.

Articles of the afore-mentioned class are often unwieldy and cumbersome to handle and hence may easily be dropped with consequent damage to the article and possible injury to the handler. This is particularly true in the handling of loaded projectiles.

In the firing of guns of medium and large caliber, a steady supply of ammunition is ordinarily provided by ammunition handlers who manually, or with the aid of a hoist, pick up the ammunition and place it in the gun or in a transfer tray for transportation to the gun. This must be done quickly in order to maintain fire power and also must be performed safely since one slip might spell disaster for the entire gun crew. The lifting and moving operation is of course fatiguing which in turn increases the hazard. Sometimes an article must be handled by means of a crane. This is especially true aboard ship. When such is the case, it is necessary that the handler be able accurately and easily to guide the projectile or other object preferably with one hand and without danger of the article slipping or being accidentally released from the carrying device.

Accordingly, it is an object of the present invention to provide a carrier for elongated cylindrical objects which is safe, convenient, and may quickly be applied to and removed from an object.

Another object is to provide a carrier of the above type which is simple in design, sturdy in construction and has a minimum number of parts.

Still another object of this invention is to provide a carrier of the above type which affords a substantial degree of protection to the object being carried.

A further object of this invention is to provide a carrier which may readily be used in conjunction with a crane by which the carrier may conveniently be guided into a desired position without danger of the article slipping from the carrier.

Other objects and advantages will become apparent during the course of the following description taken in conjunction with the accompanying drawings in which:

Fig. 1 is a perspective view of one embodiment of the present invention showing the manner of its use in handling a projectile in conjunction with a hoisting hook;

Fig. 2 is a fragmentary enlarged side eleva-

tion of the central portion of the embodiment illustrated in Fig. 1;

Fig. 3 is an enlarged rear view of the embodiment illustrated in Fig. 1;

Fig. 4 is a view corresponding to Fig. 2 but taken from above and with the projectile removed; and

Fig. 5 is an exploded perspective view somewhat reduced in size of the hinge arrangement which pivotally connects the two jaws of the carrier.

In the embodiment illustrated, the carrier may comprise a pair of semicylindrical jaw elements 6 and 7, each such element having integral therewith a rearwardly extending arm 8 at the end of each of which is an inturned flange 9 to retain in place an article being carried. The jaw elements 6 and 7 are preferably of sufficient length so that, together with the rearwardly extending arms, a major portion of the body of the object carried will be protected. To each of the jaws, a suitable shackle 29, shown in phantom in Fig. 1, may be affixed, if desired, to which guidelines can be secured in order that the carrier and its load may be guided or pulled along an inclined surface.

As shown in Fig. 5 the jaws are hingedly connected by means of a pintle 10 extending through gudgeons 11 and 12 integral with the sides of jaws 7 and 6, respectively. To facilitate engagement of an object to be lifted the jaws 6 and 7 are preferably retained in spaced relationship by suitable limit stops such as extensions 13 and 14 on gudgeon 12 and extensions 15 and 16 on gudgeon 11.

With the jaws so spaced the operator may quickly and easily engage an article to be lifted by lowering the carrier over the article thereby spreading the jaws sufficiently to engage the said article below its greatest diameter.

Integral with the top of jaw element 6 is a handle 17 for lifting the carrier and its load. A forwardly extending portion 18, which may be integral with the handle 17 as illustrated in Fig. 1, is rigidly attached to jaw element 6 and an aperture 19 may be formed in portion 18 to receive a hoist hook as indicated. The aperture 19 is preferably so located with respect to the center of gravity of the combined carrier and load that the lifting force applied by the hook is forward of the center of gravity of the object, thus tilting the carrier rearwardly to assure positive seating of the load, such as the projectile 28 in Fig. 1, on the inturned flanges 9. Spaced arms 20, rigidly mounted on the upper surface of jaw 6 extend

laterally through the opening in handle 17 so that their ends overhang the jaw 7. At the ends of the arms 20 are apertures through which a pin 21 may be inserted to form a pivot for a trigger or latch 22.

The trigger 22 has a tip 23 of the shape best illustrated in Fig. 3 which is normally urged against lug 24 by spring 25. The trigger 22 includes a finger engageable surface 26 to which pressure may be manually applied by the operator so that the tip 23 can be moved out of contact with the lug 24. It will be seen that with the above construction the jaw 6, handle 17, and the spaced arms 20 are integral and jaw 7 may be swung with respect to jaw 6; hence, the trigger 22 by engagement with lug 24 on jaw 7 will maintain it locked in a closed position when an article is grasped.

In order to prevent the trigger 22 from being accidentally moved to release jaw 7 when an object is being carried, a guard housing 27 is attached to the handle 17 which effectively protects the said trigger yet permits the operator to manipulate it when necessary.

The operation of the carrier is as follows: with a cylindrical object, such as the projectile 28 shown, lying on its side, the operator grasps the carrier by handle 17 and holding it horizontally above the object, lowers it into contact therewith with the edges of the jaws resting on the upper surface of the object. He then manipulates the trigger 22 against the pressure of spring 25 which moves tip 23 out of the path of lug 24 and permits the jaws to spread when a downward pressure is applied.

After the jaws embrace the article, the trigger 22 is released permitting spring 25 to move the trigger tip 23 towards the lug 24. As the tip 23 moves across the surface of jaw 7 it has the effect of camming jaw 7 into close engagement with the article to be lifted until lug 24 is reached. The operator may now lift the article manually or by means of a hoist hook engaged in the aperture 19 located forwardly of the handle 17. The weight of the lifted article tends to spread the jaws, however lug 24 prevents such spreading movement and the jaws are effectively and positively held closed.

When the operator wishes to release the article, trigger 22 is moved against the spring 25. This permits the jaws to spread as the carrier is lifted so as to permit the carrier to be completely disengaged. The jaws of the empty carrier close only to the extent permitted by the stops 13 and 14 on the gudgeon 12 and stops 15 and 16 on the gudgeon 11. Hence, the carrier may quickly be engaged with another article to be lifted.

It can be seen from the above description of operation that the only effort required on the part of the operator is that expended in the actual lifting of the article and carrier itself.

It is evident that many slight changes might be resorted to in the relative arrangement of parts shown and described without departing from the spirit and scope of the invention. Hence, it should be understood that the invention need not be confined to the exact construction and arrangement of parts shown and described.

The invention described herein may be manufactured and used by or for the Government of the United States of America for governmental purposes without the payment of any royalties thereon or therefor.

What is claimed is:

1. A carrier for cylindrical objects comprising a pair of hinged gripping jaws, a handle mounted on one of the jaws, a latch having a cam surface said latch being pivotally attached to one of said jaws and serving to cam the other jaw into engagement with the object to be carried, a lug on the second of said jaws against which the latch is resiliently urged to maintain the gripping jaws in article gripping position, a guard to prevent accidental release of the latch said latch having a manually engageable portion whereby it can be manually moved against the resilient pressure from contact with the said lug so that the said gripping jaws can open to engage or disengage an article.

2. A projectile carrier comprising a pair of hinged elongated projectile engaging jaws, in-turned flanges on the rearward end of said projectile engaging jaws to prevent lengthwise sliding of the projectile in the carrier when it is handled in a rearwardly tilted position, a handle mounted on one of the jaws for lifting and transporting the carrier, and an upwardly extending portion containing an aperture adapted to receive a hoist hook mounted forward of and in the same plane as said handle, said aperture being forward of the center of gravity of a projectile so that when the carrier containing a projectile is lifted by a hoist hook engaged in said aperture the carrier will be rearwardly tilted and the projectile will abut on the aforesaid in-turned flanges and be thereby prevented from sliding rearwardly in the carrier.

3. A carrier for cylindrical objects comprising a pair of hinged arcuate gripping arms, a locking lever mounted on one of them for closing the said arms in article gripping position, an upwardly extending lug on the second arm against which the locking lever is resiliently urged to maintain the arms in an article gripping position, in-turned flanges on the rear end of the arms against which the cylindrical object abuts, and shackles mounted on the forward ends of the gripping arms to which flexible hoisting elements may be attached in order to raise or lower the carrier and its load in a vertical position.

4. A carrier comprising a pair of spaced opposed article gripping jaws formed to embrace an article, said jaws being hingedly secured together along adjacent sides, a handle fixed to one of said jaws, a trigger mounted on the jaw adjacent the handle, and a lug on the other jaw and engageable by the trigger whereby the jaws may be locked together by a hand which is grasping the handle.

5. A carrier comprising a pair of spaced opposed article gripping jaws formed to embrace an article, said jaws being hingedly secured together along adjacent sides, a handle connected to the jaws adjacent the hinged connection, a finger operated latch adjacent said handle, and a cam surface on one of said jaws which is engageable by the latch to lock the jaws in article gripping position.

6. A carrier comprising a pair of spaced opposed article gripping jaws formed to embrace an article, said jaws being hingedly secured together along adjacent sides, a handle connected to the jaws adjacent the hinged connection, a finger operated latch adjacent said handle having a nose for engagement with a cam surface, and a cam surface on one of said jaws and co-operable with said nose to cam the jaws into closed position and lock them in place.

7. A projectile carrier comprising a pair of elongated projectile engaging jaws, said jaws

being hingedly secured together along adjacent sides, a latch pivotally mounted on one of said jaws and resiliently urged against the other jaw for moving it to article gripping position, and means for releasably and positively locking said jaws in article gripping position.

8. A carrier for cylindrical objects comprising a pair of gripping jaws, said jaws being hingedly secured together along adjacent sides, a releasable latch pivotally mounted on one of said jaws and bearing on the other of said jaws, resilient means urging said latch against said second jaw to move it to article gripping position, and a lug on said second jaw to provide an abutment for said latch for locking said jaws in article gripping position.

9. A carrier for cylindrical objects comprising a pair of gripping jaws, said jaws being hingedly secured together along adjacent sides, a handle mounted on said jaws, resilient means urging said jaws to article gripping position, means for

locking said jaws in article gripping position, and trigger means for simultaneously releasing said locking means and removing the force of said resilient means to enable said jaws to swing freely with respect to each other to engage or disengage an article.
